(57) **CLAIM**

The ornamental design for an seat belt shield, as shown and described.

DESCRIPTION

FIG. 1 is a perspective view of the top and front of a seat belt shield showing our new design.

FIG. 2 is a perspective view of the rear and bottom of the seat belt shield; and,

FIG. 3 is a perspective view of the seat belt shield and a reference only person wearing a seat belt drawn in phantom. It being understood that the broken lines of the seat belt strap in FIGS. 2 and 3 and the environmental matter in FIG. 3 are for illustrative purposes only and form no part of the claimed design.
